UNITED STATES PATENT OFFICE.

JESSE M. McGHEE, OF KNOXVILLE, TENNESSEE.

HIGHWAY SIGNAL FOR RAILROAD CROSSINGS.

Application filed August 19, 1921. Serial No. 483,609.

To all whom it may concern:

Be it known that JESSE M. McGHEE, a citizen of the United States, residing at Knoxville, in the county of Knox and State 5 of Tennessee, has invented certain new and useful Improvements in Highway Signals for Railroad Crossings, of which the following is a specification.

The present invention relates to signals, 10 and more particularly to that type adapted for use at intersections between public highways and railroad tracks.

An object of the invention is to provide an improved signal which may be automatically set by an oncoming train to indicate to vehicles, in particular, traversing the highway that the train is approaching the intersection so as to give suitable warning to the operators of motor vehicles and the like 20 such that they may have ample time to bring their vehicles to a stop at a safe distance from the intersection.

Another object of this invention is to provide a signal of this general character which 25 may impart not only a visual and audible indication that a train is approaching the intersection, but also give indication by actual contact so that should the operator fail to observe the visual signal and fail to 30 hear the audible signal, the contact signal will give a decided warning which cannot be well ignored.

More specifically, the invention aims at the provision of a signal which when set 35 throws a warning ray of light toward approaching vehicles on the highway, sounds a gong or other audible device which may be heard at a considerable distance, and also suspends directly over the highway and at 40 a required height a number of pendants which are arranged to contact with the vehicle to give warning by their touching, rubbing and actual contact that the signal is set for indicating danger.

The invention has for a further object 45 the provision of a relatively simple structure which may be inexpensively employed and which may be maintained in working condition at low cost, and which is durable 50 and accessible for repairs and adjustments, and a signal which will not obstruct the highway nor will be so located as liable to injury incident to traffic on the highway.

A still further object of the invention is 55 to provide a signal of this type which is so constructed that the parts thereof are

housed and protected against injury by tampering with the device or by persons who are inclined to mischievously distort the various exposed parts such as is commonly the case in employment of various types of signals which are erected in sparsely settled sections through which the highway is built.

The above, and various other objects and 60 advantages of this invention will in part be described in, and in part be understood from the following detailed description of the present preferred embodiment, the same being illustrated in the accompanying 65 drawings wherein:

Fig. 1 is a side elevation of a signal constructed according to the present invention shown in full lines in set position and erected upon a highway, the dotted lines showing 70 the position of the signal when in non-indicating position;

Fig. 2 is an enlarged fragmentary sectional view taken through an intermediate portion of the signal, showing the frame 75 for supporting the visual and audible indicating devices;

Fig. 3 is a further enlarged sectional view taken longitudinally through the outer end 80 of the signal arm and its adjacent parts;

Fig. 4 is an enlarged sectional view showing one form of operating means which may 85 be employed for actuating the signal; and,

Fig. 5 is a fragmentary section through the upper end of the signal post, showing an 90 operative connection for swinging the indicating arm.

Referring to the drawings, 10 designates a public highway of any suitable construction and which is shown in Fig. 1 as intersecting a railroad track 11. Erected at one side of the highway 10 is a post 12 of preferably hollow construction and which may be protected at its lower end by a guard or deflector 13 suitably constructed to extend 95 about and lie against the base of the post 10 at its inner and adjacent sides facing the highway 10. The guard 13 is employed for warding off vehicles and other objects which, by mismanagement, may tend to 100 strike or distort the base of the post 12.

The post 12 rises to a suitable height, and upon the upper end portion of the post is mounted a transverse shaft 14 which, when the post 12, is provided with a pinion or 110 toothed member 15 adapted to mesh with a vertical reciprocal rack bar 16, the latter

extending downwardly through the post as shown in Figs. 4 and 5 to a suitable operating mechanism. The lower end of the bar 16 is also of rack form and meshes with a pinion 17 on a shaft 18 mounted transversely in a housing 19 carrying a relatively large worm gear 20 which meshes with a worm 21 on the shaft of a motor 22. The motor 22 may be an electric motor and is adapted to be driven in any well known manner for raising and lowering the rack bar 16 and thus reciprocating the shaft 14 carried in the top of the post 12.

The shaft projects through one side of the post 12 and carries thereon a signal arm 23 which is adapted in one position to extend horizontally over the highway 10 and is of such length as to project to an appreciable extent across the highway and substantially the entire width of the same. This signal arm 23, as best shown in Fig. 3, may comprise a hollow pipe and it may be reinforced by a brace wire 24 which is secured to the inner end of the arm 23 near its shaft 14 at one end and which at the other end may be threaded through an aperture 25 formed in one side of a cap 26 which is threaded or otherwise suitably maintained upon the outer end of the arm 23.

The arm 23 carries a plurality of pendants 27 which are preferably of a flexible soft nature adapted to strike the upper portion of vehicles which attempt to pass beneath the arm 23 when lowered in order to give contact indication that the signal is set for danger. These pendants 27 may be in the nature of cords or ropes and may have wire cores to prevent cutting of the pendants and to reinforce the same against tearing and breakage. Each pendant 27 may be supported in a screw eye 28 detachably threaded into the under side of the arm 23 to admit replacement of the pendants when necessary and to facilitate assemblage of the parts of the signal.

The arm 23 is provided, at a point intermediate its inner and outer ends, with a transverse supporting frame 29 of substantially triangular shape and which may be constructed of tubing. The apex of the frame 29 is inverted and is formed of a suitable coupling member 30 having lateral branches for receiving the upwardly diverging sides of the frame and which is also threaded intermediately upon the arm 23 to facilitate assemblage of the parts. The frame 29 is constructed of opposite end members as shown in Fig. 2 and each of which may comprise a single length of tubing running upon itself at the desired angle and having inset portions or steps 31 at its corners for accommodating and protecting reflectors or lamp casings 32 which open outwardly in opposite directions from the ends of the frame. The upper part of

the frame is secured together by an upper coupling 33 which is threaded to the upper ends of the end sections of the frame and which also supports a lamp casing 34 which rises above the frame and which has in opposite sides transparent projecting panes or lenses 35 which are red and which are adapted to project red rays of light in opposite directions toward the ends of the frame. The lamp casings or reflectors 32 are also provided at their outer ends with projecting red lenses 36 adapted to also project red light in opposite directions from the ends of the frame. The lamp casings 32 and 34 each have a luminous element 37 therein and which preferably comprise an electric lamp adapted to be energized by electric current conducted through various parts of the signal in a well known manner. It may of course be preferable to independently connect the lamps 37 in parallel in the electric circuit so that should one lamp fail to illuminate, another lamp may remain illuminated without interruption.

The frame 29 is braced intermediately by an upright compression member 38 which may be threaded at opposite ends into the lower coupling 30 and upper coupling 33 and which as shown serves as a central post for a bell or gong 39 of the usual type, and which is adapted to be energized for giving an audible signal. The arrangement of the parts within and upon the frame 29 is such that the frame serves as a protector for the parts as well as a compact support. The parts are readily accessible particularly as the compression brace 38 may be provided with a union coupling 40 in its length facilitating the removal of the audible signal 39 for adjustment and repair. The coupling 33 is suitably apertured, transversely, for the reception of the brace wire 24 therethrough for supporting the same and taking up tension of the brace wire to brace the opposite ends of the arm 23 upon the intermediate portion thereof.

The signal arm 23 with its frame 29 and other parts are preferably counter-balanced by a semaphore arm 41, which is connected to the arm 23 at its juncture with the shaft 14 and which extends inwardly and oppositely from the arm 23 at a suitable angle for indicating, as shown in Fig. 1, clear and danger signals incident to the rise and fall of the arm 23.

The signal of this invention is adapted to be used in conjunction with any well known electrical device for operation upon the approach and receding of rolling stock upon the track 11. When the train approaches the crossing the motor 22 is actuated to turn in such direction as to swing the arm 23 down into a horizontal position when the visual indicating members 32 and 34 are energized to project red light rays in

opposite directions up and down the roadway and the bell or gong 39 is energized to sound the alarm of the approaching train. At the same time, the pendants 27 swing 5 into vertical position across the roadway so that if the operator or driver of a vehicle fails to heed the visual and audible signals, the pendants 27 strike against the top of the vehicle and thus give additional warning that the signal is set for danger.

The post 12 may be erected at any suitable point with respect to the intersection as it may be placed upon the left or right hand sides of the roadway and it may be 15 spaced at any suitable distance from the intersection to give ample warning to those traversing the highway. The device is so constructed that the usual semaphore operating mechanisms now employed by railroads may be used for actuating the signal, and if desired, even mechanical means may be resorted to if found practical.

It is of course understood that various changes and modifications may be made in 25 the details of construction and design of the above specifically described embodiment of the invention without departing from the spirit thereof, such changes and modifications being restricted only by the scope 30 of the following claims.

What is claimed is:

1. A highway signal for railway intersections comprising a support, a movable member carried by the support and adapted to 35 be swung into position across the highway, a visual signal carried by the member, an audible signal carried by the member, and a contact signal carried by the member for warning vehicles traversing the highway 40 when the member is set to indicate danger.

2. A highway signal for railway intersections comprising a support, an arm pivoted on the support, means for raising and lowering the arm into clear and danger indicating 45 positions, a visual signal on the arm, an audible signal on the arm, and a plurality of pendants mounted on the arm adapted to be suspended over the railway when the arm is lowered for contact with vehicles traversing the railway.

3. A highway signal for railway intersections comprising a support, an arm pivoted on the support, means for lowering the arm into position across the highway in spaced 55 relation to permit vehicles to pass beneath the arm, visual signaling means carried by the arm for indicating to vehicles the lowering of the arm into a danger indicating position, and pendants carried by the arm for contact with a vehicle passing therebeneath.

4. A highway signal for railroad intersections comprising a support, an arm movably mounted on the support and adapted 65 to be moved into position across the high-

way at a point above the same, signaling means carried by the arm for indicating the position of danger of the arm, and means suspended from the arm for contact with vehicles passing beneath the arm.

5. In a highway signal for railroad intersections, a support, an arm pivoted upon the support and adapted to be swung down across the highway to indicate danger, a transverse frame mounted on the arm, visual signals carried on the opposite ends of the frame adapted to project lengthwise of the highway in opposite directions, an audible signal mounted in the frame, and suspended means carried upon the arm adapted to contact with vehicles when the visual and audible signals are ignored.

6. A highway signal for railroad intersections comprising a support, an arm pivoted to the support and adapted to be swung down into danger indicating position across the highway, a transverse frame mounted upon the arm, a visual signal on each end of the frame projecting in the direction of the highway, an audible signal mounted within the frame for sounding an alarm when the arm is lowered, and a plurality of pendants spaced apart along the arm throughout substantially the length thereof for contact with vehicles ignoring the visual and audible signals and passing beneath the arm.

7. A highway signal for railroad intersections comprising a support, an arm pivotally mounted upon the support, means for swinging said arm downwardly into position across a highway to indicate danger, a counter-balancing semaphore connected to the arm adapted to rise and fall during the swinging of the arm to indicate clear and danger signals, signaling means carried by the arm to indicate at a distance when the arm is in lowered position, and contact signaling means carried by the arm adapted to engage vehicles passing therebeneath when said distance signaling means is ignored.

8. A highway signal for railway intersections comprising a post, an elongated arm pivotally mounted on the post, means for swinging said arms into raised and lowered positions upon the post, a transverse frame mounted upon the intermediate portion of the arm and projecting upwardly therefrom, a brace wire extending from the ends of said arm upwardly through said frame for bracing the arm and frame, lamps mounted upon the outer ends of the frame for projecting visual signals in opposite directions in the highway, a compression brace arranged in the frame for supporting said wire and frame, an audible signal mounted upon said compression brace, and a plurality of pendants spaced in said arm adapted to be suspended over the railway when said arm is lowered.

9. A highway signal for railroad intersections comprising a post, a shaft mounted transversely in the upper end of the post, means for reciprocating the shaft, an arm 5 connected to the shaft and projecting from the post and adapted to be raised and lowered upon operation of the shaft, a triangular frame mounted in inverted position upon the intermediate portion of said arm, 10 a brace wire connected to the ends of the arm and extending through the upper por-

tion of said frame to brace the frame and the arm, a plurality of signal lights mounted on the frame for indicating position of danger at opposite sides of the roadway, a 15 gong mounted in the frame for sounding a danger signal, and a plurality of pendants spaced along said arm adapted for contact with vehicles passing beneath the arms when lowered.

In testimony whereof I affix my signature.

JESSE M. McGHEE.
